UNITED STATES PATENT OFFICE.

JAMES A. CAMERON AND GUSTAF BIRGER BIRCH, OF BROOKLYN, NEW YORK,
ASSIGNORS TO CAMERON MACHINE COMPANY, OF BROOKLYN, NEW YORK, A
CORPORATION OF NEW YORK.

SLITTING AND REWINDING MACHINE.

1,326,644.

Specification of Letters Patent. Patented Dec. 30, 1919.

Application filed May 7, 1917. Serial No. 166,797.

To all whom it may concern:

Be it known that we, JAMES A. CAMERON and GUSTAF B. BIRCH, citizens of the United States, and residents of the borough of Brooklyn, in the county of Kings, city and State of New York, have invented certain new and useful Improvements in Slitting and Rewinding Machines, of which the following is a specification.

10 This invention relates generally to slitting and rewinding machines.

In the art of slitting and rewinding sheet material difficulty is at times experienced, when operating on certain materials having a pronouncedly fibrous nature, in producing such a complete separation of the web sections as to insure that no overlapping or interweaving of the web sections can take place during the rewinding operation. The 15 use of fixed separating fingers so located as to separate the sections in the course of their travel from the slitting to the rewinding means is well known. An example of one of the more successful types of slitting and 20 rewinding machines in which separating devices of this nature are employed is shown in Patent No. 1,076,189. While devices for thus acting solely on the web are effective to completely separate the web sections 25 when operating upon a great variety of materials, nevertheless there are certain materials whose nature is such that fibers continue to project from the edges of the web sections after passing the separating fingers.

30 These projecting fibers display a marked tendency to interlace, or interweave, with each other as the web sections are wound into coil formation, with the result that the contiguous coil faces are, to a greater or less extent, intermeshed, so that the individual removal of the coils from their supporting core is hampered. The main object of the 35 present invention is to produce web section separating means that will effectively prevent interweaving and overlapping of the contiguous edges of the rewound coils.

With this and other objects in view, the invention consists in providing a slitting and rewinding machine, having a top rewinding roller, with means carried by the 40 roller support to directly engage and separate the rewound coils.

In the accompanying drawing, wherein

there is shown one of the many possible embodiments of the invention,

55

Figure 1 is a vertical section of a part of a machine embodying the invention and showing a coil separating device in operative position.

Fig. 2 is a vertical section taken along the broken line 2—2 of Fig. 1.

Fig. 3 is an enlarged sectional view showing one of the separating devices in detail.

In the particular embodiment of the invention disclosed, a pair of coil supporting and surface rewinding rolls is employed which coöperate with a top rewinding roller to rewind the web sections and beneath which is mounted a cutter roll with which score-cutting disks coöperate, as in application Serial No. 146,569. There is also shown, as in the prior application, a web section separating device arranged to operate on the slitted web as it passes from the slitting to the rewinding mechanism. In addition to the slitting, separating and rewinding mechanism just described, there are also shown devices for directly engaging and separating the rewound coils themselves. These coil separating devices are preferably mounted in arms pivotally carried by a member employed for supporting the top rewinding roller and are arranged to engage the coils between the points of application of the upper and the lower rewinding rollers.

In Fig. 1 of the drawing the rewinding mechanism is shown to consist of the rewound coil supporting and rewinding rolls 1 and 2 which coöperate with the top rewinding roller 6 to wind the interposed coils 3 on the rewinding shaft 5. The rewinding shaft 5 forms a core for the rewound coils and is so mounted in the machine that it is free to rise as the diameters of the coils increase. The rewinding roller 6 is journaled in carriages 7 that are adapted to move upwardly along the vertical guide members 8 in accordance with the increase in size of the rewound coils 3.

100 The web slitting mechanism comprises the cutter roll 9 mounted beneath the rewinding rolls 1 and 2 where it coöperates with the cutting disks 12 to slit the web 4. A bracket 36 attached to the frame piece 37 serves as a bearing for the cutter roll shaft which pro-

jects through an opening 45 in the frame piece as in the companion application Serial No. 166,796, filed herewith.

It will be seen that the web 4 passes from 5 the guide roll 10 through the slitting mechanism and is then acted upon by a separating device 13, which will be hereinafter referred to, and then is drawn around the rewinding roll 2 and into place on the rewound coils 3.

10 While separating devices such as are shown at 13, for operating on a stretch of web after it has been slit into sections, are ordinarily adequate to effectively separate the web sections, it has been found that with 15 certain classes of fibrous material the use of separating devices which act wholly on the web do not, in all cases, prevent a certain amount of interweaving of the contiguous edges of the sections as they are wound into 20 place on the coils. In order to insure that interweaving of the edges of the coils will not take place, coil separating devices which take the form of thin-edge rollers 28, are arranged to be pressed into the lines of 25 separation between the web sections.

The coil separating rollers 28 are preferably carried by arms 29 pivoted to supporting brackets 30 which are slidably mounted on the bar 31 which latter rigidly connects 30 the carriages 7. The brackets 30 can be secured in any desired position along the bar 31 by means of the thumb-screws 32, in order to place the separating rollers 28 in alignment with the lines of severance produced 35 by the cutting disks 12, as is indicated in Fig. 2 of the drawing. The separating rollers 28 are preferably biased toward operative position through the pressure exerted by weights 33, one of which is carried by 40 each arm 29. A hook 34, carried by each arm is adapted to be placed over a corresponding pin 35 on the bracket 30 to hold the arms out of operative position for any reason, such as that occasioned by the removal of the completed coils.

It will be seen that separating devices of the roller type just described, by reason of the fact that they act to directly separate the rewound coils, form an effective means 50 for preventing the overlapping of contiguous edges of the coils. The coil separating rollers 28 may be used either in conjunction with the web section separating devices 13, or as the sole separating means, as will be 55 found most suitable for the character of work being performed. The use of the two forms of separating devices in the same machine forms a particularly effective means for separating the sections when the material being operated upon is of such nature 60 that rough edges, which tend to interweave, are produced by the slitting operation.

Each of the separating devices 13, which operate to separate the sections in the web 65 stretch between the slitting and the rewind-

ing mechanism, consists of a blade pivotally mounted in a bracket 25 slidably mounted on the supporting bar 26 and adapted to be locked in any desired position by means of the thumb-screw 27. The pivotal mounting 70 of the separating blade, as shown in Fig. 1 of the drawing, facilitates the threading of the web because this arrangement permits the separating blades to be readily swung to positions where they will not intercept the 75 web stretch while the threading operation is being performed.

In Fig. 1 of the drawing is shown a stripper member 46, which is mounted to bear against the surface of the cutter roll. Two 80 such stripper members are employed and they are mounted so as to be adjusted along the supporting shaft 47 to take positions where they will deflect from the roll the narrow trimming strips that are produced 85 at the edges of the web and prevent the carrying of the strips through the rewinding mechanism with the slitted web.

Any suitable driving mechanism for the cutter and the rewinding rolls may be employed: For instance the drive pulley 38 has integral therewith a pinion 48 which meshes with gear 41. The gear 41 is in turn rigidly connected to a pinion 49 meshing with driving gear 50 of the cutter roll 95 shaft and gears 51 and 52 on the shafts of the rewinding rolls 1 and 2.

What is claimed is:

1. A slitting and rewinding machine comprising: means for slitting a web of sheet material into sections, means for rewinding the sections into coils including a pressure roller engaging the upper surface of the coils, a movable carriage, displaceable as the diameter of the rewound coils increases, 100 supporting said pressure roller, and a separating member mounted on the carriage independently of the pressure roller to engage and separate adjoining coils.

2. A slitting and rewinding machine comprising: means for slitting a web of sheet material into sections, means for rewinding the sections into coils including a pressure roller engaging the upper surface of the coils, a movable carriage, displaceable 110 as the diameter of the rewound coils increases, supporting said pressure roller, and a separating member pivotally mounted on the carriage independently of the pressure roller biased to engage and separate adjoining coils.

3. A slitting and rewinding machine comprising: means for slitting a web of sheet material into sections, means for rewinding the sections into coils including a pressure roller engaging the upper surface of the coils, a movable carriage, displaceable as the diameter of the rewound coils increases, 125 supporting said pressure roller, and a plurality of separating members mounted on 130

- the carriage independently of the pressure roller, and means for individually pressing the separating members into engagement with the rewound material between adjoining coils.
4. A slitting and rewinding machine comprising: means for slitting a web of sheet material into sections, means for rewinding the sections into coils including a pressure roller engaging the upper surface of the coils, a movable carriage, displaceable as the diameter of the rewound coils increases, supporting said pressure roller, and a plurality of separating members pivotally mounted on the carriage independently of the pressure roller, and means for individually pressing the separating members into engagement with the rewound material between adjoining coils.
5. A slitting and rewinding machine comprising: means for slitting a web into sections, means including two lower surface rewinding rollers and a top pressure rewinding roller for rewinding the slitted sections into side-by-side coils, a support carrying said top pressure rewinding roller and automatically displaced by increase in diameter of the rewound coils, and separating means mounted on said support and biased independently of the support toward the rewound coils to engage between adjacent coils.
6. A slitting and rewinding machine comprising: means for slitting a web into sections, means including two lower surface

rewinding rolls and an upper pressure rewinding roller for rewinding the slitted sections into side-by-side coils, a main support automatically displaced by increase in diameter of the rewound coils and carrying 40 said pressure rewinding roller, separating means engaging between adjacent rewound coils, and means for disengaging the separating means from the coils independently 45 of the movement of the main support including a pivotal support mounted on the main support and carrying the separating means and means normally urging the separating means into engagement between adjacent rewound coils.

7. A slitting and rewinding machine comprising: means for slitting a web into sections, means for rewinding the slitted sections into side-by-side coils, a main support automatically displaced by increase in 50 diameter of the rewound coils, separating means engaging between adjacent rewound coils, and means for disengaging the separating means from the coils independently 55 of the movement of the main support including a pivotal support mounted on the main support and carrying the separating means and means normally urging the separating means into engagement between adjacent rewound coils.

Signed at Brooklyn, New York city, in the county of Kings and State of New York, this 3d day of May, A. D. 1917.

JAMES A. CAMERON.
GUSTAF BIRGER BIRCH.
